MASSAGE TABLE

James B. Stewart, Flint, Mich.

Application June 10, 1957, Serial No. 664,595

22 Claims. (Cl. 128—33)

The present invention relates to method of massage as well as improvements in table apparatus on which a human body may sit or recline and be subject to mechanical vibrations. Such tables are well known in the art and they have gone into limited use particularly in connection with physical therapy.

It is the main object of the present invention to provide a table of the class described in which improvements have been made in the arrangement, construction and operation of the vibrating means and in the areas of vibration so as to simulate the effects of Swedish massage.

Another object is to provide an apparatus of the type described in which the supporting surface of the table is subjected to selective and localized areas of vibration.

Another object of the invention is to provide an apparatus of the type described in which there is a plurality of sources of vibration, said sources having both general and localized vibrational effects upon the body supporting surface of the table, the frequency and amplitude of the vibration of each source being selectively controlled.

A further object is to provide a vibratory table for simulating Swedish massage characterized by surges or out-of-phase vibrations which (a) impart a rippling action to the muscles of the body, (b) provide a gentle manipulation of the joints, and (c) subject the areas of the body engaging the table surface with a gentle hacking or pounding motion.

A still further object of the invention resides in a method of simulating Swedish massage by imposing vibrations to produce surges and out-of-phase conditions upon a vibratory table surface.

A still further object is to provide an improved method of simulating Swedish massage in which a resiliently supported surface vibrates at one frequency and as localized areas within the same surface vibrating at a different and variable frequency.

Another object of the invention is to provide a method of simulating Swedish massage comprising steps of impressing a vibration of higher frequency lower amplitude upon a body supporting surface having an existing vibration of lower frequency higher amplitude.

A still further object is to provide a method of subjecting a human body to vibrations simulating Swedish massage comprising the steps of supporting the body upon a surface having a consistency comparable to human flesh and vibrating the support at out-of-phase frequencies to provide surges of impressed vibrations to the body supporting surface.

These and other objects and advantages of the invention will appear from the following specification and claims.

In the drawings,

Fig. 1 is a plan view of a table taken from below,

Fig. 2 is a side-elevational view of Fig. 1,

Fig. 3 is a diagrammatic layout showing the vibrating members removed from the table frame,

2

Fig. 4 is a perspective view of eccentric weight shown removed from the motor shaft,

Fig. 5 is a cross-sectional view of the table taken on line V—V of Fig. 1,

Fig. 6 is a view similar to Fig. 5 taken on line VI—VI of Fig. 1,

Fig. 7 is an enlarged detailed view of the control panel shown in Fig. 2,

Fig. 8 is an enlarged detailed view shown in vertical cross-section of the spring supporting and vibrating structure,

Fig. 9 is a diagrammatic illustration of the action of one of the vibrated members, and

Fig. 10 is a diagrammatic layout of the electrical circuit.

Referring to the illustrated form of the invention, the table 10 is shown with a head end 12, a foot end 14, supporting legs 16, and a top supporting massage surface 18. The rigid vertical sides and ends 20 give marginal support to the pad 22. A control panel 24 is shown attached to one side 20.

In practice, the table 10 is approximately seven feet in length to permit an adult person of normal height to comfortably recline upon the pad with the width approximately three feet to support the body well within the sides 20. A main vibrating frame 26 which in the illustrated and above described form may be roughly two feet by six feet, is of relatively rigid structure. As shown the sides 28 of the frame 26 are of inverted U-section with L-section ends 30.

Sides 20 may be of plywood to which longitudinally extending L-section rails 32 are attached to give support to the springs 34 which in turn give support to the sides 28 of the frame 26. As shown, springs 34 are coiled with a lower horizontal projection 36 having an eye to receive a suitable fastener for securing the springs 34 to the rails 32. The remainder of the springs 34 are shown coiled about a vertical axis with an eye at the upper end to receive a suitable fastener for the attachment of the upper ends of each spring 34 to the sides 28. Space blocks 38 are shown inserted into the channels of the sides 28 at the location of each spring 34. Parallel to the ends 30 are spaced inverted T-section cross members 40, 42 and 44 attached at their outer ends to the sides 28. The L-section cross members 45, parallel to the sides 28, and extending between the end 30 and member 40 and between the member 40 and the member 42, complete the main vibrating frame 26.

The marginal support of the pad 22 by the sides and end 20 is supplemented by a plurality of planar members 46, 46' which are shown of rectangular shape but of varying area. The members 46 have their upper surfaces cushioned by the pad 22 and the members 46 together with their associated springs 48 and motors 50' collectively define cushioned massage structures for selective massage of various parts of the body, as will be more fully described. The location, number and area of the members 46 depends upon the area of support and selective vibration of the pad 22 desired. For convenience of disclosure, the members 46 giving support to various areas of the pad 22 upon which various portions of the body are disposed, are shown in Fig. 3 removed from the table 10 and have been given the following legends: RS (right arm and shoulder), LS (left arm and shoulder), RL (right leg), LL (left leg), HS (hip and tip of spine), RH (right side of hips), LH (left side of hips), B (lumbar region) H (thoracic region), and F (feet). Members 46' shown on opposite sides of the area F function to support the pad 22 upon opposite sides of the area F which support the feet.

The members 46, 46' are supported from the mem-

bers 28, 30, 40, 42, 44 and 45 of the frame 26 through springs 48 which may correspond in form and mounting to the springs 34. In Fig. 8 the manner in which the members 46, 46' are attached to the upper end eye of the springs 48 is clearly shown.

For providing general vibration of the pad 22 solely through vibration of the frame 26, an electric motor 50 is shown in Fig. 5 mounted from the cross member 42 of the frame 26. Rotor shaft 52 of the motor 50 is shown unbalanced by off center weights 54 attached thereto. Rotation of the motor 50 will vibrate the frame 26 on the springs 34. This vibration is transmitted through the springs 48 to the members 46, 46' and hence to the pad 22.

In the illustrated embodiment, each member 46 has depending therefrom on a pair of springs 56, a motor 50' which may correspond in all respects to the motor 50 on the frame 26.

Referring to Fig. 7, the control panel 24 has an "off" and "on" toggle switch 58 for controlling the cooling fan 60 which draws air in through the grill 62 and blows it into the interior of the table 10 to remove the heat of the motors and rheostats. An indicator light 64 is located in the electrical circuit of the fan 60 to show that the fan is operating. Switch 66 is connected in circuit with the rheostats 68 and the dial selector 70 through which the speed and selective operation of the motors 50, 50' is controlled. Preferably, several of the motors 50' have dual control in that in addition to their selection and operation through the selector 70, they each have an independent circuit. Thus, the switch 72 and rheostat 74 controls the motor 50' of the RH area of Fig. 3; switch 76 and rheostat 78 controls the motor 50' of LH area; switch 80 and rheostat 82 controls the motor 50' of RL area; switch 84 and rheostat 86 controls the motor 50' of LL area. Obviously this arrangement may be extended to cover with individual control each of the members 46.

In Fig. 10 is shown the electrical wiring diagram in which the grounded three-prong plug 88 carries three wires, the ground wire being connected to the frame 26 and 110 v. alternating current being carried by the other two wires to the control panel 24 and hence to the various electric motors. For convenience, the motors 50, 50' have been numbered 1 to 11 in Fig. 10 and conforms to stations 1 to 11 on the dial selector 70 of Fig. 7. It will also be noted from Fig. 7 that the stations 2 to 11 of the selector 70 are keyed to the areas RS, LS, RL, LL, HS, RH, LH, B, H and F of Fig. 3.

To describe in greater detail certain of the components of my improved table, in the present commercial form of my invention for the adult table motors 50, 50' having a rated $\frac{1}{30}$ H.P. and wound to be regulated over the desired speed range by the rheostats and weighing approximately 1 lb. 8 oz. give satisfactory performance with the frame 26 of light section aluminum. Springs 34 and 48 are wound in the manner of the spring 48 shown in greater detail in Fig. 8, being of conical shape with the overall length $2\frac{3}{4}$ ", with a taper from top to bottom of $1\frac{3}{4}$ " to $1\frac{1}{4}$ ". The springs 34, 48 and 56 are wound from .155" hard drawn steel spring wire. Spring 56, as shown in Fig. 8 is conically wound with an overall length of $2\frac{1}{4}$ " with a taper from top to bottom of $1\frac{1}{4}$ " to $1\frac{3}{4}$ ".

While it must be appreciated that the simulation of Swedish massage may be accomplished within the scope of the present invention in varying degrees, I have found that with the motors 50, 50' and the springs 34, 48 and 56 of the design described above in detail that excellent results are obtained if the weights 54 upon opposite ends of the shaft 52 of each motor 50, 50' is fabricated from $\frac{3}{4}$ " hexagonal aluminum bar stock with a length of 2" and with the $\frac{1}{4}$ " cross hole 54 located $\frac{3}{8}$ " from one end. The weight of such a piece of material will be approximately $1\frac{1}{2}$ oz.

I have found that the firmness or consistency of the pad 22 as fabricated and supported on the members 46, 46'

gives the best results when it is comparable to the fleshy part of the human body. As shown in Fig. 8, in practice the member 46 is $\frac{1}{4}$ " plywood, the lower side of the pad light weight canvas, the upper side a durable, attractive plastic covering with the core of sponge rubber or foamed plastic of the desired consistency.

Fig. 9 is a diagrammatic showing, illustrating the gyration of the members 46 in their relationship to the pad 22 and the frame 26. With the members 46 marginally supported on the springs 48 and the motors 50' depending from the pair of springs 56, the out-of-balance forces on the shafts 52 cause the members 46 to vibrate about a neutral axis, the amplitude depending upon the speed of the motors. It will be understood that the load upon the pad 22 will effect the amplitude of the members 46 and that as a result the amplitude of the shaft 52 will not necessarily conform to that of the members 46.

To simulate Swedish massage, my improved table has been designed to be capable of a sequence of manipulations employed in Swedish massage. To this end the dial selector 70 has a normal rotatable switching knob 90 capable upon rotation to selectively connect the electrical conductor 92 with any one of the electrical conductors 94 of positions 1 to 10 of the dial selector 70, all in a well known manner. With the knob 90 at station 1, as shown in Fig. 10, and the switch 66 "on," motor 50, No. 1 of Fig. 10, will cause the frame 26 to vibrate and the entire area of the pad 22 will be subjected to a generally uniform vibration, the frequency of which may be varied by rotating the rheostat 68. Under these conditions the entire body of a person reclined upon the pad 22 will be subjected to a gentle massage.

Rotation of the knob 90 clockwise from station 1 to station 2 will stop motor 50 and the vibration of the frame 26 thereby and start motor No. 2 of Fig. 10 of the ten different motors 50' depending from the members 46. This will cause vibration of the member 46 associated with the area RS of Fig. 3 and the portion of the pad 22 immediately supported by area RS will be vibrated in the manner shown in Fig. 9 and the right arm and shoulder muscle will be massaged with the frequency of vibration controlled by rotating the rheostat 68 between its high and low positions. With the knob 90 rotated from station 2 to station 3, the No. 3 motor of Fig. 10 will be operated, the area LS of Fig. 3 will be vibrated and the left arm and shoulder muscle will be massaged. Proceeding in a similar manner from station 4 to station 11, inclusive, will result in the massaging sequences of right leg, left leg, hips and tip of spine, right side of hips, left side of hips, lumbar region, thoracic region, and feet. In each of stations 1 to 11 it will be understood that the motors No. 1 to No. 11 inclusive, may have their speed of rotation and the resulting frequency of amplitude of vibration varied by manipulating the rheostat 68.

With the switch 66 "off" and switch 72 "on," motor No. 7 is started and the area RH is vibrated. At the same time, if switch 78 is turned "on," motor No. 8 is operated and the area LH is vibrated along with the area RH. Thus, both the right and left sides of the hips may be simultaneously massaged. By adjustment of the rheostats 74 and 78 the vibration of the area RH may be different than area LH and surges and out-of-phase conditions of vibration will be set up on the areas RH and LH which are transmitted to the immediate adjacent areas of the pad 22 and hence to the hip area of the reclined body. As the weight and position of the body upon the pad 22 will effect the form and amplitude of the surges and out-of-phase condition of vibration, some manipulation of the rheostats 74 and 78 is required to obtain the desired condition of operation.

The massage characteristics of the pad 22 may be further regulated and altered with the switch 66 "on" and the knob 90 at station No. 1. This will result in the frame 26 being generally vibrated by the motor 50 (No.

1 of Fig. 10) at one selected frequency and a portion of the superstructure of the frame 26 being independently vibrated at the same or different frequency with any one or more of the switches 72, 76, 80 or 84 in "on" position. With this arrangement it becomes possible to impress one frequency and amplitude of vibration of the pad 22 upon another frequency and amplitude of vibration.

It will be understood that from the layout of the control panel of Fig. 7 and from the wiring diagram of Fig. 10 that with the switch 66 "off" any one or all of the motors No. 2, 4, 5, 7 and 8 may be independently and variably operated either alone or in desired combinations. With the switch 66 "on," any one of the motors Nos. 1, 2, 3, 6, 9, 10 and 11 may be operated by manipulating the knob 90 simultaneously with all or any one or more of the motors Nos. 4, 5, 7 and 8. While it has been found necessary in practice, if desired, the individual control provided for the motors 4, 5, 7 and 8 may be extended to include any one or more of the remaining motors.

In practice, it may be desired to massage the feet or thoracic region with high frequency, low amplitude vibration while at the same time subjecting the hip area to surges of lower frequency, high amplitude. This can be accomplished (1) with the switch 66 "on" and the knob 90 at either station 10 or 11 and the rheostat 68 adjusted for high motor speed and (2) with the switches 72 and 76 "on" and the rheostats 74 and 78 adjusted to give the desired frequency, amplitude and surge conditions. Moreover, other combinations and arrangements for massaging different parts of the body at the same time under different conditions will readily occur to those skilled in the art of massage and physical therapy.

Having thus described my invention what I claim is novel and desire to protect by Letters Patent is:

1. A massage table comprising an upper cushion massage surface, fixed margin support structure for said surface, movable support structure for said surface disposed between said margin support and below said surface, said movable support structure including a planar and relatively stiff member disposed parallel to said surface in direct supporting relation thereto, a frame spaced below said surface and said planar member and carried by said margin supporting structure, compression springs disposed between said planar member and said frame, and an out of balance rotor spring mounted on the under side of said planar member and having its rotational axis parallel to said surface and said planar member.

2. A table of the type described for simulating Swedish massage comprising a base structure, a body supporting massage pad, a main frame structure for the indirect support of said pad, resilient means for supporting said main frame from said base structure, means mounted on said main frame to vibrate the same, means defining areas of localized and direct support for the underside of said pad, resilient means for supporting said areas of support from said main frame and means mounted on said areas of support for imparting localized vibration to said pad.

3. A table as defined in claim 2, wherein said means for defining said areas of support are in the form of relatively rigid members having a planar surface for supporting the under side of said pad.

4. A table as defined in claim 3 wherein the means for vibrating said members are resiliently mounted on said members.

5. A table as defined in claim 3 wherein the means for vibrating said members are electric out-of-balance rotary vibrators, and springs for mounting said vibrators on said members.

6. A table as defined in claim 3 wherein the means for vibrating said members take the form of out-of-balance rotary vibrators, and spring means attached to the underside of said members from which said vibrators depend.

7. A table for simulating Swedish massage comprising

a horizontally disposed pad, a fixed margin support structure for said pad, a main vibrating frame disposed within said support structure and beneath said pad, spring disposed between said frame and said support structure, an out-of-balance rotary vibrator supported on said main frame for rotation about an axis substantially parallel to said main frame, flat support members for said pad engaging the under side of said pad and spaced inwardly from said margin support structure for said pad, spring means disposed between said members and said main frame to give support to said pad, spring means depending from said members, and out-of-balance rotary vibrators carried on said depending spring means for rotation about axes parallel to said pad to vibrate said members independently of each other and of said main frame.

8. A table as defined in claim 7 wherein all of said spring means are in the form of spring coils.

9. A table as defined in claim 7 wherein said vibrators are in the form of electric motors having out-of-balance rotors.

10. A table as defined in claim 9 wherein means are provided to selectively control the rate of rotation of said motors and thus the frequency and amplitude of vibration of said main frame and said members.

11. In a vibrataing massage device of the class described, a horizontally disposed supporting pad, a flat member engaging the under side of said pad, coil springs giving margin support to said member, a pair of coil springs depending from said member within the margin area of said support by said first springs, a motor suspended from said pair of springs and having an out-of-balance rotor disposed substantially parallel to the plane of said flat member and of said pad.

12. In a vibrating table of the class described as set forth in claim 11 wherein said pair of springs are disposed upon opposite sides of the central axis of said flat member, about which axis said member is caused to vibrate by the out-of-balance forces of said rotor.

13. A table for supporting and vibrating the human body comprising a top pad surface upon which the body may recline, means giving margin support to said pad, a main vibratory frame substantially coextensive with said pad within its marginal support, spring means supporting said frame from said first means, a plurality of separate members giving support to the under side of said pad within the margin support of said first means, spring means giving separate support to said members from said frame, said members giving localized support to said pad in areas of said pad upon which various members of the human body are adapted to engage, means for vibrating said frame to vibrate all of said members from said frame, and means to selectively vibrate said members independently of the source of vibration of said frame.

14. A table as defined in claim 13 wherein the frequency of vibration of said vibrating means may be varied.

15. A table as defined in claim 13 wherein said members each have an area of support at least approximating the projected area of that portion of an adult human body to be supported, namely, the head, upper back, lower back, right and left shoulders, right and left legs, feet and buttock.

16. In a vibrating massage device, a supporting surface to be vibrated to effect massage, coil springs having their axis of compression disposed substantially normal to said surface, means connecting an end of said springs to said surface, a vibrating motor having attachment structure, and means for connecting the other end of said coil springs to said attachment structure.

17. A massage table comprising an upper cushioned massage surface, means for giving marginal support to said surface, vibrated means for giving support to said surface within said marginal support, said vibrated means including upper and lower relatively rigid support struc-

tures, resilient means located between said structures and spacing the same, a vibrating motor attached to said lower structure, and spring means connected between said first means and said lower structure giving marginal support to said lower structure.

18. A massage table as defined in claim 17 wherein said rigid upper support structure gives said upper cushioned massage surface spaced localized support to vibrate said massage surface in localized areas.

19. A vibrating massage device comprising an outer massage surface upon which the body to be massaged is directly supported, a vibrated support for said massage surface including a relatively rigid flat member disposed parallel to said massage surface, cushioning means disposed between said surfaces, said vibrated support having a second relatively rigid member disposed parallel to said first rigid member, resilient means disposed between said members, a vibrating motor attached to said second rigid member, and resilient means connected to said second rigid member for giving marginal support to said second rigid member.

20. A vibrating massage device comprising a cushioned outer massage surface structure having rigid marginal support structure for said massage surface, a localized vibrating support for said outer surface, said support including a flat relatively rigid member disposed in parallelism with said massage surface, a vibrating motor, a resilient connection between said motor and said rigid member, and a resilient marginal support structure between said rigid members and said rigid marginal support structure for said massage surface.

21. A massage table for simulating Swedish massage comprising a plurality of cushioned massaging structures collectively defining a support in substantially a horizontal plane and upon which a person reclines, said structures being horizontally spaced and located to present individual support to various parts of the body of the re-

clining person, each of said structures having a relatively rigid horizontal support member, cushioning structure disposed upon the upper surface of said support member, an electric vibrator unit associated with each of said

5 support members and attached to the under surface of said support members, frame structure for giving support to said massaging structures, spring means extending between said support members and said frame structure, and an electrical circuit for individually and selectively controlling said vibrator units to selectively massage different parts of the body, said circuit including means for varying the frequency and the amplitude of the vibration of said units and said support members to which they are attached.

15 22. A massage table for simulating Swedish massage comprising a plurality of individual massaging structures transversely and longitudinally arranged and spaced to present a horizontal support for a reclining person, said structures being spaced and arranged to be located so as to give support to the shoulders, hips, thighs, and feet, each said structure having a relatively flat horizontally disposed rigid support member having a cushioned upper surface, an electric vibrator unit mounted upon the lower surface of each of said support members, frame structures for giving support to said massage structures, spring means extending between the border of said support members and said frame structure, and an electric circuit having control means therein for selectively regulating the operation of said units.
